UNITED STATES PATENT OFFICE.

GEORGE J. THEOBALD, OF BOSTON, MASSACHUSETTS, ASSIGNOR OF ONE-HALF TO WILLIAM L. ELLIOTT, OF BOSTON, MASSACHUSETTS.

SADDLETREE.

SPECIFICATION forming part of Letters Patent No. 781,695, dated February 7, 1905.

Application filed July 25, 1904. Serial No. 217,924.

To all whom it may concern:

Be it known that I, GEORGE J. THEOBALD, a citizen of the United States, residing at Boston, county of Suffolk, State of Massachusetts, have 5 invented an Improvement in Saddletrees, of which the following description, in connection with the accompanying drawings, is a specification, like numerals on the drawings representing like parts.

10 This invention has for its object to provide a novel saddletree for harnesses in which the back-band passing through said saddletree will have a flat bearing on the skirt and the bottom of the passage-way in which said back-band 15 is received, whereby all bends in the band are avoided.

The novel features of my invention will be more fully hereinafter described and then pointed out in the claims.

20 Figure 1 of the drawings is a central section of a saddletree embodying my invention, the back-band, skirt, and jockey being omitted from one-half said figure. Fig. 2 is a top view of one arm of the saddletree with the skirt and jockey partly broken out to better show the construction. Fig. 3 is a central vertical section of one end of the saddletree, showing a modified form of the invention. Fig. 4 is a plan view of Fig. 3.

25 The saddletree is formed with the two side arms 3 and 4, which are curved to the proper shape and are connected together at their central portions and at their ends by sunken bridges 5 and 6, this construction being extremely common in saddletrees. Said arms form between them a passage through which extends the usual back-band 9, to which the thill-straps are connected, said back-band resting on the sunken bridges 5 and 6 and being 30 free to slide through the passage while the harness is in use. Projecting from each bridge 6 at the lower end of the saddletree and offset therefrom is a seat 7 for supporting and stiffening the skirt 8, said seat being offset from 35 the bridge a distance substantially equal to the thickness of said skirt. The result of this construction is that the top of the skirt occupies the same plane as the bridge 6, and the back-band 9 has, therefore, a flat bearing on

the skirt and bridge and extends in a straight 50 line from the top of the saddletree down to and beyond the skirt. This construction permits the back-band to slide freely in the saddletree without being bent at all as it passes over the skirt, and thus obviates all unnecessary wear upon the back-band. In prior saddletrees, so far as I am aware, the seat for supporting the skirt has always been placed in the same plane as the bridge 6 and forms, in effect, an extension of said bridge. With 60 this construction it is necessary to skive the inner edge of the skirt in order not to form an abrupt shoulder at the skirt edge over which the back-band must pass, and even then the back-band has to bend more or less in 65 order to pass over the skirt. The seat 7 serves also to stiffen the skirt and takes the place of ordinary stiffening member, which is usually inserted beneath the skirt to prevent it from cracking or breaking at the edge of the bridge. 70

10 designates the usual jockey which lies on top of the arm of the saddletree and covers the back-band, said jockey at its edges being sewed to the arms of the skirt, as at 11.

12 designates a jockey-tip, which is secured 75 to the arms 3 and 4 and lies over the back-band 9, said jockey-tip being preferably made of brass or some similar material, thus constituting a part of the trimmings of the harness. Said jockey-tip has the two arms 13, which 80 overlie and are secured to the arms 3 and 4, said latter arms being cut away to receive the arms 13, as best seen in Fig. 2, and the cross-piece 14, which connects said arms and lies over the back-band 9, thus forming a guide 85 for the latter. The thickness of the cross-piece 14 is preferably substantially the same as that of the jockey, as seen at the left, Fig. 1. In lieu of the form of jockey-tip shown in Figs. 1 and 2 I may use that shown in Figs. 90 3 and 4, in which the jockey-tip is arranged to be secured to the bridge 6 instead of to the arms 3 and 4. This form of jockey-tip comprises the base-plate 16, the side members 17, provided with the outwardly-extending 95 flanges 18 and connected by the cross-piece 19, said parts being shaped to form an opening 20, through which the back-band extends.

Where this form of jockey-tip is used, the side pieces 3 and 4 are cut away on their inner edges, as shown at 21, sufficiently to receive the side pieces 17 of the jockey-tip, so that the inner sides thereof will stand flush with the sides 23 of the arms 3 and 4. With this construction there are no shoulders present which the edges of the back-band 9 can rub against, as there usually is where the form 10 of jockey-tip shown in Figs. 3 and 4 is used.

In making my invention I have endeavored to remove all possible shoulders or inequalities against which the back-band 9 is liable to rub. The back-band can be very easily inserted in my improved saddletree, and because there are no shoulders against which the band rubs and as said band does not have to bend in passing over the skirt it will wear very much longer than when used in saddletrees as 15 commonly constructed.

I propose to make the saddletree of aluminium or some similar metal which is strong, but extremely light. Saddletrees are now commonly made of cast-iron, and as a result the 20 weight of the saddletrees for heavy harnesses is such as to materially fatigue the horse and also oftentimes causes sore backs. By making the saddletree of aluminium its weight is reduced by several pounds, much to 25 30 the relief of the horse.

Various changes in the construction of the device may be made without departing from the invention.

Having fully described my invention, what I claim as new, and desire to secure by Letters 35 Patent, is—

1. A saddletree having side arms forming between them a space for the back-band, said arms being connected at their lower ends by a sunken bridge on which the back-band directly 40 rests, and a seat for supporting the skirt, said seat projecting beyond the bridge and being offset therefrom a distance substantially equal to the thickness of the skirt.

2. A saddletree having side arms forming 45 between them a space for the back-band, said arms being connected at their lower ends by sunken bridges on which the back-band rests, a seat 7 projecting from each bridge and offset therefrom a distance substantially equal to the 50 thickness of the skirt, and a jockey-tip detachably secured to each side arm and occupying a position above the seat.

In testimony whereof I have signed my name to this specification in the presence of two sub- 55 scribing witnesses.

GEO. J. THEOBALD.
